UNITED STATES PATENT OFFICE.

JOSEPH P. GLASER, OF DETROIT, MICHIGAN, AND BENJAMIN W. BURCH, OF BALTIMORE, MARYLAND, ASSIGNORS TO CHAMBERLIN METAL WEATHER STRIP COMPANY, OF DETROIT, MICHIGAN, A CORPORATION OF MICHIGAN.

WEATHER-STRIP FOR METAL WINDOW SASHES AND FRAMES.

1,261,920.

Specification of Letters Patent.

Patented Apr. 9, 1918.

Application filed August 18, 1915. Serial No. 46,073.

To all whom it may concern:

Be it known that JOSEPH P. GLASER, a citizen of the United States, residing at Detroit, in the county of Wayne and State of Michigan, (whose post-office address is 327 Hubbard Ave., Detroit, Mich.) and BENJAMIN W. BURCH, a citizen of the United States, residing at Baltimore, State of Maryland, (whose post-office address is 123 E. 10 Fayette St., Baltimore, Md.,) have invented certain new and useful Improvements in Weather-Strips for Metal Window Sashes and Frames, of which the following is a specification, reference being had therein to 15 the accompanying drawings.

This invention relates to improvements in sheet metal weather strips, and has for its primary object the provision of an improved type of strip adapted to meet the conditions of service attending the employment 20 of metallic window casings and frames therefor.

Experience in the metal window art has demonstrated the fact that weather stripping as ordinarily formed for use in connection with the usual wooden sashes or frames is not altogether practical in the metal window and sash art because of its failure to meet the differing conditions existing in the 25 use of metal in lieu of wood. Owing to the relative rigidity of metal frames and sashes, and the corresponding unyielding nature thereof, considerably more flexibility for freedom of movement between the weather 30 strip members must be afforded, while at the same time preserving sealing engagement therebetween; and for the same reason the surfaces of the metallic parts where uneven or irregular cannot be sealed by merely 35 superposing a sheet metal strip thereupon but require the addition of other means to 40 meet the exigencies of the case.

With these considerations in mind, as well 45 as other matters to be later pointed out, the present improvements may be said to reside in the provision of two coöperating sheet metal members, one adapted to be mounted on the window frame and the other on the window casing, associated with means for

attaching the base members of the said 5 weather strip parts in relation to the casing and sash to which they are respectively attached with interposed packing of suitable nature to seal the points of attachment; and including a special formation of the parts 55 of the weather strip whereby ample flexibility is permitted to accommodate for the shifting or adjusting movements of the sash relative to the frame, while maintaining a constant sealing engagement between the 60 two parts of the strip, and more specifically what is known as a "line" engagement therebetween as distinguished from wide surface engagement, the latter resulting in undue friction between the opposing surfaces and 65 operating to some extent against the flexibility desired.

The invention further has for its object the formation of the weather strip members so that they may be placed on the face of 70 the window sash and exposed adjacent portions of the casing to present a neat finished appearance while offering the expected protection under all weather conditions to be met; the arrangement and formation enabling the joining as by mitering of the 75 strip members at the corners to be continuous around the top, bottom and sides of the casing to the end that the said corners are better sealed and protected than has 80 heretofore been found possible.

In the accompanying drawings forming part hereof, we have illustrated two embodiments of the invention which are believed to be sufficient to impart a full understanding 85 of the improvements, but it will be understood by persons skilled in this art that the invention is capable of embodiment in still other forms and arrangements without departing from the spirit thereof, all as may 90 be in keeping with the hereto appended claim.

In the drawings:

Figure 1 is a horizontal sectional view, through a metal window frame and associated window sashes, the latter being shown merely in a fragmentary way, provided with the improved window stripping;

Fig. 2 is an enlarged sectional view through the coöperating members of the weather strip;

Fig. 3 is a face view of one of the sashes 3 and the window frame showing the weather strip in position thereon and presenting the continuous formation thereof, flowing from the mitered corners of the strip and,

Fig. 4 is a view similar to Fig. 2, of a 10 slightly modified construction.

Referring more specifically to the drawings wherein like reference letters designate corresponding parts in the several views, A represents a window frame of any suitable 15 construction or configuration, that shown being of metal bent to provide the shape desired to present the usual parting bead B, the outer confining moldings or strips C, and the pair of runways D for the window 20 sashes.

E represents a pair of sashes upper and lower, formed of metal bent in the form shown, or in any other way found practical or expedient.

H designates the base of one of the weather strip members, both of which are formed of sheet metal, preferably of a 25 springy character, for example, brass, and J is an upstanding sealing rib formed by offsetting the metal from the base H and bending the same upon itself, as clearly indicated.

K is the base part of the coöperating weather strip which is bent outwardly at 30 right angles, as indicated at L, and again bent inwardly as at M and upon itself as at N, to provide a double-walled sealing rib M—N, the return bend portion N being bent to occupy a position parallel to the portion 35 L, represented at O, and terminating in a flanged portion P occupying a converging relation with the double walled rib M—N. The flanges or ribs P and M—N, present a restricted mouth or opening Q into which 40 the sealing rib J first above mentioned may project and have sliding engagement along opposite contact lines S.

The marginal edge or flange P is rounded, as shown at T, to simulate rounding of the 45 edge U of the double wall M—N, these edges facilitating the smooth engagement of the contacting parts.

The base flanges H and K of the two weather strip members, in the case of a 50 wooden sash frame, might be secured directly against the latter, but in the case of a metal sash and frame such engagement would not result in a sealing contact, and to create a desired seal, the edges of the base 55 flanges H and K are turned inwardly, as at W, W', and within the hollow of the strip thus formed, suitable packing such as felt X, is interposed, the edges W, W' embedding

therein to assist in holding the same in place and effecting a perfect seal while the whole 60 surface of the packing is pressed against the metal sash and metal frame as the case may be, by forcing the base flanges H and K thereagainst by means of fastening screws Y. These fastening screws are of a special 65 and improved nature, the threads thereof being formed so that the spiral groove intermediate of the convolutions of the threads is approximately of a width the thickness of the metal forming the sash frame and window 70 casing. In securing the parts in place the screws are forced through the metal bases H and K by permitting the screw to form its own opening therethrough and the same is true of the engagement of the screws 75 with the sash and window casing so that by merely turning the screw through the metal or sash and casing the thickness of the metal 80 of the walls of the latter will permit seating of the walls in the groove of the screw 85 and hugging the threads in a wedging action. This has been found to be practical, and secure and obviates the necessity of providing specially threaded portions for the reception of the screws, usually regarded as 90 necessary where the thinness of the metal engaged by the screws will not permit the forming of threads therein.

In that form of the invention illustrated in Fig. 4, the base flange K' is bent to underlie the intermediate portion L' to enable the fastening of the strip to the form of metal window sash disclosed in this figure. This simply demonstrates the ease with which the strip may be formed to meet the 100 conditions controlling the service thereof in connection with window sashes of different types.

In both embodiments of the invention it will be seen that the bending of the female 105 members of the strip provides various points of yield or flexibility which will permit the interfitting strip members to preserve their sealing lines of engagement, while always being of a nature to give or play in keeping 110 with whatever freedom of movement may exist between the window sash and frame.

Another important consideration in connection with the present improved type of strip is that the same may be installed 115 completely around the frame of the window, that is to present a continuous sealing at the top, sides, bottom and corners of the window, the latter being frequently difficult to seal with weather stripping heretofore 120 known in the art, especially where yieldability of the parts is contemplated. The joints at the corners are accomplished by mitering the ends of the strip members, as will be readily understood from the foregoing 125 suggestions.

Having thus described the invention, what is claimed is:

A weather stripping for windows comprising a male member having an attaching base, 5 and a female member for receiving the male member having an attaching flange located outwardly beyond its receiving part, and a yielding portion extending at an angle across the closed edge and along one side 10 of the receiving part and spaced therefrom.

In testimony whereof we hereunto affix our signatures.

JOSEPH P. GLASER.
